(57) **CLAIM**

The ornamental design for a tire, as shown and described.

DESCRIPTION

FIG. 1 is a perspective view of a tire showing my new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is an enlarged cross-sectional view taken along line 8-8 in FIG. 2; and,

FIG. 9 is an enlarged view of the portion 9-9 and 9'-9' in FIG. 6.

The broken lines immediately adjacent subject matter shown in solid lines represent boundaries of the claim and form no part thereof.
